UNITED STATES PATENT OFFICE.

JOHN REINSCHMIDT, OF NEW YORK, N. Y.

UNDERGARMENT.

1,271,082.

Specification of Letters Patent.

Patented July 2, 1918.

Application filed September 1, 1917. Serial No. 129,261.

To all whom it may concern:

Be it known that I, JOHN REINSCHMIDT, a citizen of the United States, and resident of the borough of the Bronx, county of the Bronx, city and State of New York, have invented certain new and useful Improvements in Undergarments, of which the following is a specification.

My invention relates to undergarments and more particularly to that type thereof commonly known as union suits and has for its object to provide a garment which, when worn, will completely cover the person of the wearer in any and all positions which he may assume. At the same time it is the purpose of my invention to so construct the garment that the parts of the wearer are readily accessible even though the crotch is closed and the usual rear opening is omitted. In addition I propose to provide a garment which is easily put on and taken off and which is capable of being quickly adjusted to provide a rear opening of maximum extent and comfort particularly when the wearer is in a sitting position. Other objects of my improvement will appear from the description hereinafter and the features of novelty will be pointed out in the appended claims.

In the accompanying drawings, which for the purpose of illustration and description show two forms of my invention, Figure 1 is a front elevation of one form of garment and Fig. 2 is a similar view of another form.

As shown in the illustrated examples the garment may comprise the usual upper or body portion 5, having a neck opening 6 and sleeves or arm openings 7 and combined with the customary leg sections 8; any suitable material may be utilized in the construction of the garment and insertions of relatively elastic material 9 or any other features customarily found in union suits may be included if desired.

In the form shown in Fig. 1 the garment opens at the front from the neck opening 6 to the lower end of one leg section 8, the opening extending along a continuous straight line 10 in close proximity to and within easy reaching distance of the crotch 11 but not through it, so that an opening at the crotch is avoided. As shown in Fig. 2 the front opening extends along a straight line 10^a from the neck opening 6 to a point in the neighborhood of the waist line, then transversely and from the waist line down

to the lower end of a leg section along the straight line 10^b. This line 10^b also extends in close proximity to and within easy reaching distance of the crotch 11 but not through it so that in this form also the usual opening at the crotch is avoided. Any suitable means may be provided for maintaining the garments in a closed condition as for instance-buttons 12 and buttonholes 13 located so as to properly coöperate.

It will be seen, in both forms illustrated, that at least from the waist line downward the line of the front opening is offset from the vertical median line of the garment but is located in close proximity thereto. With this arrangement the crotch section of the garment is closed but is within easy reach of that part of the front opening which is adjacent thereto; the parts of the wearer are thus readily accessible but normally are fully covered. My improved garment is also without the usual rear opening and is continuous and smooth at this portion so that here also the person of the wearer is normally covered. When it is desired to expose the posterior portion of the wearer's anatomy the fastening devices 12 and 13 from the waist downward are disconnected. This leaves the outer portion of the one leg section 8 free to be turned completely to the rear in the form of a flap, the location of the lower portion of the front opening being such as to provide for a maximum rear opening and a maximum of comfort for the wearer particularly when in a sitting posture.

On account of simplicity of construction the garment is extremely cheap to produce; it also provides absolute smoothness throughout thus avoiding the formation of folds and creases which chafe and irritate the wearer. The garment is also easy to put on and easy to take off and is extremely cool and sanitary. It will, of course, be obvious that my invention is capable of being embodied in undergarments and particularly union suits of types other than those illustrated.

Various changes in the specific forms shown and described may be made within the scope of the claims without departing from the spirit of my invention.

I claim:

1. A union suit having a permanently closed crotch and permanently closed at the back and having opposed front sections

2
forming a front opening extending from the neck opening to the lower end of one leg section, at least those portions of the opposed edges of said front sections which 5 project downwardly from the waist line extending along a common continuous line offset relatively to and substantially parallel with the longitudinal median line of the front of the garment and located in close 10 proximity to the closed crotch and means for detachably connecting the front sections.

2. A union suit having a closed crotch and

closed at the back and having a front opening extending along a continuous straight line from the neck opening to the lower end 15 of one of the leg sections, said opening being off-set relatively to and substantially parallel with the longitudinal median line of the garment and located within easy reaching distance of the closed crotch.

In testimony whereof I have hereunto set 20 my hand.

JOHN REINSCHMIDT.
